SHOE TREE

Edward H. Clark, Danville, Ill.

Application April 28, 1941, Serial No. 390,832

3 Claims. (Cl. 12—129.4)

This invention relates to shoe trees, and its general object is to provide a shoe tree or form that includes means for heating a shoe, to effect drying thereof, thus increasing the life of the shoe, preserving its shape and safeguarding the health of the wearer, by preventing colds and illness due to the wearing of a shoe which is cold and damp.

An important object is to provide a shoe tree that includes a hollow toe member shaped to follow the shape of the shoe and having an electric light bulb supported therein to heat the air and cause circulation thereof by expansion, so as to ventilate the interior of the shoe and render the same dry, sanitary and free from odor.

A further object is to provide a shoe tree of the adjustable type that is equipped with heating means for the purpose set forth and it is simple in construction, inexpensive to manufacture and extremely efficient in use and service.

This invention also consists in certain other features of construction and in the combination and arrangement of the several parts, to be hereinafter fully described, illustrated in the accompanying drawing and specifically pointed out in the appended claims.

In describing the invention in detail, reference will be had to the accompanying drawing wherein like characters denote like or corresponding parts throughout the several views, and in which:

Figure 1 is a top plan view illustrating a pair of trees constructed in accordance with one form of the present invention.

Figure 2 is a sectional view taken approximately on line 2—2 of Figure 1, looking in the direction of the arrows.

Figure 3 is a sectional view taken approximately on line 3—3 of Figure 1, looking in the direction of the arrows.

Figure 4 is a longitudinal sectional view taken through the body or toe portion of a modified form.

Figure 5 is a transverse sectional view taken through the form of Figure 4.

It will be obvious that the trees are furnished in pairs, one for each shoe of a pair, and as each tree of each form is identical, the description of one tree of each form will suffice.

Referring particularly to the form of Figures 1 to 3, it will be noted that the tree includes a hollow body 1 providing a toe member tapered in rounded formation toward its forward end and otherwise shaped to follow the shape of the upper of a shoe at the toe and vamp portions thereof, and of a length to extend from the tip of the toe

portion to the upper end of the vamp portion, as will be obvious upon inspection of Figure 1. The rear end and bottom of the body are completely open as best shown in Figures 2 and 3 and the lower edge of the body will rest upon the sole of the shoe, so that the body actually provides what may be termed a heating chamber opening toward the rear of the shoe only, when the tree is inserted therein.

10 Mounted in and fixed to the upper end portion of the body laterally of the longitudinal center thereof is an attaching bracket including depending parallel ears 2 having pivotally connected thereto one end of a link member 3 and pivotally connected to the opposite end of the member 3 is a threaded collar 4 having threaded therein a screw shank 5 of a substantially ball shaped heel receiving member 6. The forward end of the shank has a serrated abutment disk 7 fixed there-
20 to to prevent removal of the shank from the collar and threaded on the shank is a locknut 8 to hold the shank fixed in adjusted positions.

Secured within the hollow body 1 by screws 9 or the like for disposal in bridging relation to the 25 sides of the body is a supporting member 10 for the socket member 11 of an electric light bulb 12, the member 10 being in the form of a partition having upper and lower longitudinally disposed recesses 13 and 14 therein to provide for the free passage of air into and out of the body as shown by the arrows in Figure 2. The ends of the supporting member 10 follow the shape of the body at the sides thereof for snugly fitting the same and the member 10 is provided with an 30 opening for the socket member 11, the latter being mounted in the opening and provided with a flanged cap 15, with the flange 16 thereof engaged with the rear face of the supporting member to cooperate with the flange 17 of the body of the 35 socket member, that engages the front face, to prevent casual removal thereof from the member 10, as will be apparent upon inspection of Figure 2. However, the cap of the socket member is threaded on the body thereof so as to allow ready removal for replacement or repairs.

The opening is arranged so that the bulb is elevated a considerable distance above the lower edge of the body and consequently above the shoe sole when the tree is in use, and the bulb is spaced 40 from the wall of the body so as to provide complete circulation of air about the same. Adhesively or otherwise secured to the inner face of the upper wall of the body to overlie the bulb is a piece 18 of sheet asbestos to prevent the top of the body from being overheated by the heated air

rising from the bulb and so that the heat will be more readily deflected for passage through the recess 13.

The form of tree of Figures 4 and 5 is identical to the other form in all respects, with the exception that instead of having a supporting member in the form of a partition, for the light bulb, the supporting member of the form of Figures 4 and 5 is provided by a tongue 19 struck from the rear end portion of the body or toe portion 20 adjacent the top thereof, and bent downwardly for disposal in depending relation therefrom. The tongue is of a length to terminate above the lower edge of the body 20 and has an opening therein with a socket member 21 mounted within the opening and held accordingly by a threaded cap 22, and mounted in the socket member 21 is a light bulb 23.

The socket members of each form have one of the ends of conductor cords 24 connected thereto and the opposite ends of the cords 24 are provided with prong type plug members 25, which as shown in Figure 1 are plugged in a three-way connector member 26 having a switch member 27 connected thereto for controlling the circuit to the light bulbs, as will be apparent. By that arrangement, it will be obvious that a pair of trees can be associated and electrically connected to a single unit.

From the foregoing, it will be further obvious that when the trees are inserted within a pair of shoes and the bulbs illuminated, the air within the bodies 1 or 20 as the case may be will be heated and caused to expand, to bring about circulation of the air through the body, as indicated by the arrows in Figure 2, thus ventilating the interior of the shoes for the purpose set forth, and at the same time the shoes are held in proper shape through the instrumentality of the bodies and the ball shaped heel receiving members 6.

It is thought from the foregoing description that the advantages and novel features of the invention will be readily apparent.

It is to be understood that changes may be made in the construction and in the combination and arrangement of the several parts, provided that such changes fall within the scope of the appended claims.

What I claim is:

1. A shoe tree comprising a hollow body providing a toe member shaped to fit the toe and vamp portions of a shoe and having an open rear end and bottom, adjustable heel receiving means pivotally connected to the body, vertical supporting means fixed within the body and

spaced a considerable distance from the rear end thereof, said supporting means being also spaced from the inner face of certain wall portions of the body to allow free passage of air into and out of the body, an electric socket member fixed to the supporting means, a conductor cord connected to the socket member, a light bulb mounted in the socket member to heat the air within the body to bring about circulation thereof to ventilate the shoe, and a sheet of asbestos secured to the inner face of the upper wall of the body and overlying the bulb.

2. A shoe tree comprising a hollow body providing a toe member shaped to fit the toe and vamp portions of a shoe and having an open rear end and bottom, adjustable heel receiving means connected to the body, supporting means within the body and being in the form of a partition bridging said body and fixed thereto, said supporting means having an opening therein and formed with a pair of elongated recesses extending longitudinally along the upper and lower portions of the supporting means, the lower recess providing an air inlet and the upper recess an air outlet cooperating with the inlet for free passage of air into and out of the body, an electric socket member fixed within the opening, a conductor cord connected to the socket member, a light bulb mounted in the socket member for disposal horizontally within the body inwardly of the supporting means to heat the air in the body to bring about circulation thereof to ventilate the shoe, and a sheet of heat resisting material overlying the bulb.

3. A shoe tree comprising a hollow body formed from sheet material to provide a toe member shaped to fit the toe and vamp portions of a shoe and having an open rear end and bottom, adjustable heel receiving means pivotally connected to the body, a tongue struck from the rear end of the body and along the length of the upper portion thereof and being bent for disposal in depending relation from the body, said tongue having an opening therein and being of a width to be spaced from the sides of the body to allow for free passage of air into and out of the body, an electric light socket member fixed within the opening, a conductor connected to the socket member, a light bulb mounted in the socket for disposal horizontally within the body inwardly of the tongue to heat the air in the body to bring about circulation thereof to ventilate the shoe, and a sheet of heat resisting material overlying the bulb.

EDWARD H. CLARK.
